UNITED STATES PATENT OFFICE.

WALTER R. McCLANAHAN AND CHARLES E. BELL, OF TERRA ALTA, WEST VIRGINIA.

CUSPIDOR.

SPECIFICATION forming part of Letters Patent No. 718,650, dated January 20, 1903.

Application filed April 18, 1902. Serial No. 103,547. (No model.)

To all whom it may concern:

Be it known that we, WALTER R. McCLANAHAN and CHARLES E. BELL, citizens of the United States, residing at Terra Alta, in the county of Preston and State of West Virginia, have made certain new and useful Improvements in Cuspidors, of which the following is a specification.

This invention is an improvement in cuspidors, especially those designed for use in cars and similar vehicles and in public places—such as hotels, offices, &c.; and the invention consists in certain novel constructions and combinations of parts, as will be hereinafter described and claimed.

In the drawings, Figure 1 is a top plan view of the cuspidor in position for use. Fig. 2 is a cross-section on about line 2 2 of Fig. 1. Fig. 3 is a cross-section on about line 3 3 of Fig. 1, parts being broken away and the sections of the receptacle being shown closed in full lines and open in dotted lines. Fig. 4 is a cross-section on about line 4 4 of Fig. 1, showing the sections of the receptacle with the lids open and the bottom sections closed; and Fig. 5 is a detail perspective view of one of the sections of the receptacle, and Fig. 6 is a detail section.

In carrying out our invention we provide a suitable framing A, which may be readily secured in place in the floor B of the frame in which the cuspidor is to be used, and this framing A is provided with the main chamber A', which receives the so-called "receptacle," presently described, and the chambers A² at the opposite sides of the chamber A', and which receives the operating wheels or devices C, by which the sections of the receptacle are swung to open and close the same. The chamber A' of the casing is open at the top, while the chambers A² are closed at their upper sides by cap-plates a², which are secured by screws a³, so they can be conveniently removed when desired, and these cap-plates are provided with openings a', through which project segments of the operating-wheels C, which segments are preferably ruffed, so they can be conveniently operated by the foot. These wheels C may be termed "rockers," as by rocking them the receptacle can be opened or closed, and in connection

with the rockers we provide means in connection with the sections of the cuspidor so the said sections can be readily adjusted to open position, as desired. Ordinarily the devices 55 are so weighted that the receptacle will automatically adjust to the closed position shown in Figs. 1 and 2 and full lines, Fig. 3, from the position shown in Fig. 4 when the foot is removed from the rocker.

In the construction shown the receptacle comprises two sections D, which are alike, and one of which is shown in Fig. 5, and which may be combined and adjusted to the position shown in Fig. 4 to form a receptacle in the 65 use of the cuspidor. As the sections D are constructed and operated similarly, the description of one will answer for both. We form these sections with lids D' and bottom wings D² and pivot the sections at the junction of said lid and wing at E, so the sections can rock from the closed position shown in Figs. 1 and 2 to the open position shown in Fig. 4, and vice versa. While our invention might operate to a certain extent with the 75 single section D, in which case the lid D' of such section will be formed to serve as a cover for the upper end of the chamber A', we prefer to employ the two sections, to hinge them oppositely, as shown, to operate them by 80 means of a rocker or rockers arranged between the pivots D² of the sections, and to connect them with the said rocker or rockers in the manner presently described. It will be noticed that the free edges of the lids D' 85 may be formed to fit each other, to which end one edge may be rounded, as shown at 1 in Fig. 4, and the other edge curved, as shown at 2 in the same figure, so when adjusted to the position shown in Fig. 1 the lids will fit 90 snugly together at their adjacent edges. It will also be noticed that the lid and bottom wing of each section are arranged at approximately a right angle to each other and with the bottom wings dipped or curved slightly 95 to properly serve the purpose and facilitate their draining when adjusted to the position shown in Fig. 3.

In pivoting the sections D they are provided at their ends with shaft sections or trunnions 100 E, journaled at a in the casing and provided with crank-arms F, which are connected by

pitmen G with the rockers C, the pitmen being connected with the rockers eccentrically and preferably at diametrically opposite points, so the turning of said rocker in one direction will operate both sections of the receptacle, as desired. The casing is provided at d with narrow ledges or shoulders on which the lids of the receptacle rest when closed, as shown in Fig. 1, and the casing is slotted from its upper edge to receive the trunnions E of the sections D and the shafts C' of the rockers C, so the parts C and D can be readily adjusted to place when the caps A² are removed. This also permits convenient access to the parts for any desired purpose.

In the operation of the device, when the sections D are in the position shown in Figs. 1 and 2 and full lines, Fig. 3, if the rocker C be turned in either direction it will operate through the pitman G to adjust the sections D to the full-line position shown in Fig. 4, as will be understood by a comparison of Figs. 3 and 4. To ease or cushion the stopping of the sections D in both opened and closed positions, we provide a buffer H, preferably of spring metal, having the wings H' and H² for engagement by a stud I on one of the crank-arms B, as shown in Fig. 3, the said buffer being arranged for engagement by the stud I in both positions of the sections D, as will be understood from the drawings and the foregoing description. In operation, it will be noticed, the cuspidor is self dumping or draining and is always closed, as shown in Fig. 1, except when positively operated to the open position, (shown in Fig. 4,) from which position it automatically closes when the pressure of the foot is released from the rocker.

Manifestly the size of the cuspidor may be varied as desired. It also can be operated from one side by the use of one rocker C or from both sides, as shown, and one or both sections may be rocked, or the receptacle may comprise but one section, as may be desired.

The lids, wings, trunnions, and cranks can all be cast in one piece.

As best shown in Figs. 4 and 6, the main chamber may have a chute or extension J to pass through the ceiling under the floor of the coach whenever desired.

As shown in Fig. 3, both ends of the buffering-spring are arranged to be engaged by the crank-arm. When the cuspidor is to be used as a self or automatic closer, one arm H' might be omitted. It will be understood that the chute J may be made in different shapes for convenience in making connections with pipes in offices, &c.

Having thus described our invention, what we claim as new, and desire to secure by Letters Patent, is—

1. The cuspidor herein described, comprising in connection with a suitable framing, the receptacle composed of the opposite sections each having a lid and a bottom wing, and provided with trunnions at the juncture of said wings, said trunnions having crank-arms, the

rockers at the opposite sides of the said receptacle and between the pivots of the sections and arranged for operation by the foot, the pitmen connecting said rockers with the opposite sections of the receptacle, the buffer by which to ease or cushion the stopping of the receptacle in both adjustments, and the stud on the crank-arm of one of the receptacle-sections to engage said buffer, substantially as set forth. 75

2. A cuspidor having a receptacle composed of two opposite sections each having a lid and a bottom wing and pivoted at the juncture of said wings, and means whereby said sections may be opened and closed, substantially as set forth. 80

3. In a cuspidor substantially as described, the receptacle comprising the section having a bottom wing and a lid connected therewith, and pivoted at the juncture of said lid and wing, and means whereby the said section may be operated, substantially as set forth. 85

4. A cuspidor comprising the receptacle-section having a bottom wing and a lid pivoted at the juncture of said lid and wing and provided with a crank-arm, the rocker arranged for operation by the foot, and the pitman connecting said rocker with the crank-arm of the receptacle-section, substantially as set forth. 90

5. The combination of the framing having a main chamber and the side chambers at the opposite sides of the main chamber, and the caps for the side chambers provided with openings for the rockers, the rockers operating in the side chambers, the receptacle having its sections operating in the main chamber and provided at the ends of said chamber with trunnions extending into the side chambers and having crank-arms operating in the side chambers at the ends thereof, and the pitmen connecting said crank-arms with the rockers, substantially as set forth. 105

6. A cuspidor comprising two sections combined to form the receptacle and each composed of a lid and bottom wings and pivoted whereby they may be adjusted to opened or closed position, and foot-operated means for actuating said sections, substantially as set forth. 110

7. A cuspidor comprising a receptacle having a section formed with a bottom wing and a lid at approximately right angles to each other and pivoted at the juncture of said lid and wing, and foot-operated means by which said section may be rocked to different positions, substantially as set forth. 120

8. The combination of the framing having an opening and the receptacle composed of two sections, each section being provided with a lid and with a bottom wing, the two lids being formed when combined to close the opening in the framing and the two bottom wings when combined and abutted, to form the body of the receptacle beneath said opening, and means for operating the sections, substantially as set forth. 125

9. The framing having bearings for the shafts of the rockers and for the shafts of the receptacle-sections, the receptacle-sections having shafts journaled in the casing and formed with lids, and with bottom wings, the crank-arms on the shafts of the said sections, the rockers having shafts journaled in the bearings of the framing, and pitmen connect- ing the cranks of the receptacle-sections with the rockers, substantially as set forth.
